UNITED STATES PATENT OFFICE

2,159,800

HEAT TREATING APPARATUS

Karl H. Keller, Cleveland Heights, Ohio, assignor
to General Electric Company, a corporation of
New York

Application April 7, 1938, Serial No. 200,717

6 Claims. (Cl. 266—5)

My invention relates to heat treating apparatus and more particularly to apparatus for automatically heat treating the end portions of wires or similar articles, such as the leading-in wires for incandescent electric lamps or the like.

It is sometimes desirable to heat treat the inner end portions of leading-in wires which are attached to a lamp filament in order to drive off the occluded gas therein and to anneal them, in accordance with the disclosure in Patent 1,992,798, W. P. Zabel, February 26, 1935. If this is not done, the occluded gases in the said end portions of the leads are liberated by the heat of the filament and cause early failure of the said filament. Moreover, the ends of the leading-in wires in some cases are so hard and rigid, particularly in the larger sizes, as to interfere with the proper attachment of the filament. Moreover, the heat treatment of the end portions of the lead wires reduces the intensity of vibrations transmitted to the filament and thus increases the life of the lamp.

One of the objects of my invention is to provide apparatus for automatically heat treating the end portions of leading-in wires economically on a commercial scale of production. Another object of my invention is to provide apparatus for this purpose which accurately controls the heat treatment and confines it to a definite length of the wires. Other features and advantages of my invention will be apparent from the description which follows and from the accompanying drawing of one species thereof.

In the drawing, Fig. 1 is a plan view of apparatus comprising my invention; Fig. 2 is a section thereof along the dot-dash line 2—2 of Fig. 1; Fig. 3 is a side elevation showing the heat treating fires, the ends of the leading-in wires being treated and adjacent parts of the apparatus; and Fig. 4 is a perspective view, on an enlarged scale, of a plug member for supporting a bundle of wires and admitting gas thereto.

The machine shown in the drawing comprises a plurality (six) of heads 10 mounted at equally spaced intervals about the periphery of the turret 11 which is indexed in a counter-clockwise direction in movements of only 30 degrees, although the heads 10 are spaced 60 degrees apart. Each head 10 is, in this instance, adapted to treat a bundle of 200 leading-in wires 12 which are located within the paper tube 13 and are inserted into tubular holders 15 of the heads 10 at either station I or II. The holders 15 have flanged ends 15'—15" and are located within cylindrical shells 16. The said holders 15 are preferably provided

in a variety of sizes to hold loosely various sizes of bundles of wires. The end of paper tube 13, which extends beyond the lower end of the leading-in wires 12, rests on the adjustable plug 17 in the holder 15 which frictionally engages the walls of the holder and is so located therein as to cause the upper end portions of the leading-in wires 12, which are to be heat treated, to extend above the shell 16. Usually only one-half to one-quarter inch of the ends of the leading-in wires is heat treated. The vertically extending shell 16, as shown, is mounted directly on an arm 18 extending from the turret 11 and is closed at its lower end by said arm 18. The turret 11 is supported by means (not shown) engaging the hollow shaft 19 and is indexed at intervals by the wheel 20 which is located on the lower end of said shaft 19 and carries a roller 21 for each head 10 on the turret 11. As each head is represented by a roller, the indexing motion consists in advancing the roller to the position occupied by the preceding roller. The indexing takes place when one of the rollers 21 is engaged by the curved portion 24 of a cam 22 mounted on shaft 23. While the heads are not in motion, they are held in position by the presence of the uncurved portion of cam 22 between two of the rollers. Patent 2,021,001 shows this common form of indexing apparatus in greater detail.

The indexing movement of the turret 11 carrying the heads 10 into station II causes a reducing gas, in this case hydrogen, to be admitted into the bottom of the shell 16 through the opening 25 and to pass through holes 25' (Fig. 4) in plug 17 to displace the air in the holder 15 around the bundle of leading-in wires 12. The gas reaches the opening 25 through the valve 26 which is connected thereto by the pipe 17 and is also connected to the upper chamber 28 in the distributing manifold 29 by the pipe 30. The valve 26 is provided with a pin 31 which controls the gas flow therethrough and which is moved back therein (or radially outward) by engagement with the rise of the cam 32. The movement of the pin 31 compresses the spring 33 and removes the flanged head 31' of the pin 31 from its seat in the valve 26 to permit the gas to flow. The distributing manifold 29 is mounted on the supporting bracket 34 on the turret 11 and receives the reducing gas from a source (not shown) through the pipe 35 which is sealed by the packing 36. The arm 37 prevents the pipe 35 from turning with the distributing manifold 29.

Following the loading operation, the heads 10 are indexed to station III which causes them to

pass burner 38 and be carried under the burners 39, 40 and 41 as shown in Fig. 3. The function of burner 38 is simply to ignite the hydrogen escaping from the top of the head 10. Burners 39, 5 40 and 41 and the similar set of burners 42, 43 and 44 located at station IV direct a very concentrated flame onto the upper end portions of the leading-in wires 12 which are raised to a temperature of more than 940° C. during the 12 10 seconds indexing period used and are annealed to $\frac{1}{4}$ inch back from the end. In the particular case shown, the portions of the usual three-part leading-in wires 12 being treated are made of nickel and their upper ends are bent back to form open hooks which hold said wires 12 a little apart. 15 Because of the hooks, the leading-in wires 12 form a tapering mass which is wedged into the end of paper tube 13 which in turn protects the very pliable portions of the wires within the tube 20 13.

The portions of the leading-in wires 12 extending beyond the shell 16 are oxidized during the heat treatment but those portions within the sleeve 16 are protected by the reducing gas there- 25 in which excludes the atmosphere and cools the leading-in wires 12 so that they are not materially heated below the top edge of the sleeve 16. To produce the necessary cooling effect, the reducing gas is cooled both by contact with the 30 distributing manifold 29 and the holder 15, the former of which is cooled by a flow of water through the lower chamber 45 therein and the latter of which is cooled indirectly through the sleeve 16 by the subsequent flow of the water 35 through the coil 46 surrounding said sleeve 16. The cooling water enters the chamber 45 from a source not shown through the pipe 47 which extends down through the hollow shaft 19 and is held against rotation by a stationary member 40 not shown. The pipe 47 is sealed to the distributing manifold 29 by the packing 48. In leaving the chamber 45, the water passes through each 45 of the pipes 49 which is coiled to form a coil 46 which is soldered directly to a shell 16, the water then flowing out the other end of the pipe 49 50 which is located over the draining trough 50. The drain trough 50 extends completely around the turret 11 under the draining ends of the pipes 49 and empties into the pipe 51. A valve 52 is 55 provided at the bottom of the sleeve 16 to drain away water condensing therein because of its coolness.

The hydrogen escaping from the top of the sleeve 16 continues to burn after the heads 10 55 are indexed from station IV and even burns above the hole in the top of a cap 53 which is placed over said sleeve 16 midway between stations IV and V. The cap 53 is hinged to the hollow post 54 extending upward from the turret 60 11 and is tipped into place on the sleeve 16 by an upward movement of a rod 55 located within the hollow post 54. Movement of the rod 55 is caused by the indexing movement which carries the lower end of said rod over the inclined surface of the cam 56 mounted on a stationary part 65 of the apparatus. The purpose of the cap 53 is to gather and hold the hydrogen flowing upward through the shell 16 about the ends of the leading-in wires 12 to cause the oxide thereon to be reduced, to prevent the atmosphere from coming in contact with them and causing further oxidation, and to increase their rate of cooling. The cap 53 is preferably provided with a flanged 70 lower rim 53' which seats on the top of the shell 16 and retards the escape of hydrogen there- 75

between. The said cap is also provided with fins 57 which radiate some of the heat absorbed by the cap 53.

During the interval in which the heads 10 are being indexed around to station X, the hydrogen continues to flow thereinto and the leading-in wires 12 are cooling, so that when station X is reached they no longer need the protection thereof and the flow of hydrogen is cut off. The flow of hydrogen is cut off by the pin 31 of valve 26 10 which passes over a drop portion of cam 32 at this station. The indexing motion carrying the head 10 from station X carries the pin 58 extending from the side of the cap 53 into contact with a stationary cam 59 having a rising contour 15 which lifts the pin 58 and the cap 53 from the shell 16 to a point where the cap 53 falls back onto the end of the rod 55. No operations are performed at stations XI and XII, and the bundles of treated leading-in wires 12 are removed 20 from the heads 10 at these points.

While I have shown one species of my invention, it will be obvious to those skilled in the art that various changes, additions or substitutions may be made therein without departing from the 25 spirit of my invention.

What I claim as new and desire to secure by Letters Patent of the United States is:

1. In apparatus of the type described, the combination of a holder for enclosing all but an end of a bundle of wires to be heat treated, a burner mounted adjacent said holder and arranged to direct a flame onto the exposed end of said bundle of wires, means for introducing a reducing gas into said holder, a cap adapted to be placed over the exposed end of said bundle of wires after the heat treatment of the end thereof to confine the reducing gas and reduce oxidation of the wires, and cooling means surrounding said 40 holder.

2. In apparatus of the type described, the combination of a turret arranged to be indexed intermittently, a plurality of heads mounted on said turret each comprising a holder for enclosing all but an end of a bundle of wires to be heat treated, a cap mounted adjacent said holder and arranged to be moved over to enclose the exposed end of the bundle of wires protruding therefrom, and means for introducing a reducing gas into 45 said holder, a burner located at an indexing station of said turret and arranged to direct a flame against the exposed end of the bundle of wires in each of said heads, and means for moving the said caps on each of said heads over the said 50 end of the bundle of wires in the adjacent holder when said holder has been indexed away from the station occupied by said burner.

3. In apparatus of the type described, the combination of a turret arranged to be indexed intermittently, a plurality of heads mounted on said turret each comprising a holder for enclosing all but an end of a bundle of wires to be heat treated, a cap mounted adjacent said holder and arranged to be moved over to enclose the exposed 60 end of the bundle of wires protruding therefrom, means for introducing a reducing gas into said holder, and means surrounding said holder for conducting a cooling liquid thereabout, a burner located at an indexing station of the turret and 65 arranged to direct a flame against the exposed end of the bundle of wires in each of said heads, and means for moving the said caps on each of said heads over the said end of the bundle of wires in the adjacent holder when said holder 70

has been indexed away from the station occupied by said burner.

4. In apparatus of the type described, the combination of a turret arranged to be indexed intermittently, a plurality of heads located on said turret each comprising a vertically disposed sleeve, a tubular holder located in said sleeve and adapted to hold a bundle of wires with the upper end thereof extending upwardly beyond the top 10 of said sleeve, a cap mounted adjacent said sleeve, means for introducing a reducing gas into the lower end of the sleeve, a burner located at an indexing station of said turret and arranged to direct a flame against the exposed upper end of 15 the bundle of wires in each of said heads, and means for moving the said caps on each of said heads over the said upper end of the bundle of wires in the adjacent holder when said holder has been indexed away from the station occupied 20 by said burner.

5. In apparatus of the type described, the combination of a turret arranged to be indexed intermittently, a plurality of heads located on said turret each comprising a vertically disposed 25 sleeve, a tubular holder located in said sleeve and adapted to hold a bundle of wires with the upper end thereof extending upwardly beyond the top of said sleeve, a cap mounted adjacent said sleeve, means for introducing a reducing gas into 30 the lower end of the sleeve, a tubular coil closely surrounding said sleeve for conducting a cooling liquid thereabout, a valve mounted adjacent each head for controlling the flow of reducing gas thereto, a cam mounted on the axis of rotation of said turret and engaged by the valve in each of said heads for discontinuing the flow of reducing gas at loading and unloading stations of the heads, a burner located at an indexing station of said turret and arranged to direct a flame against the exposed upper end of the bundle of wires in each of said heads, and means for moving the said caps on each of said heads over the said upper end of the bundle of wires in the adjacent holder when said holder 35 has been indexed away from the station occupied by said burner.

bundle of wires in each of said heads, and means for moving the said caps on each of said heads over the said upper end of the bundle of wires in the adjacent holder when said holder has been indexed away from the station occupied by said 5 burner.

6. In apparatus of the type described, the combination of a turret arranged to be indexed intermittently, a plurality of heads located on said turret each comprising a vertically disposed sleeve, a tubular holder located in said sleeve and adapted to hold a bundle of wires with the upper end thereof extending upwardly beyond the top 10 of said sleeve, a cap mounted adjacent said sleeve, means for introducing a reducing gas into 15 the lower end of said sleeve, and a tubular coil closely surrounding said sleeve for conducting a cooling liquid thereabout, a valve mounted adjacent each head for controlling the flow of reducing gas thereto, a cam mounted on the axis 20 of rotation of said turret and engaged by the valve in each of said heads for discontinuing the flow of reducing gas at loading and unloading stations of the heads, a burner located at an indexing station of said turret and arranged to 25 direct a flame against the exposed upper end of the bundle of wires in each of said heads, and means for moving the said caps on each of said heads over the said upper end of the bundle of wires in the adjacent holder when said holder 30 has been indexed away from the station occupied by said burner.

KARL H. KELLER.
